UNITED STATES PATENT OFFICE.

GEORGE W. BARRATT, OF BELLEVUE, PENNSYLVANIA.

HAMMOCK.

No. 866,322.

Specification of Letters Patent.

Patented Sept. 17, 1907.

Application filed June 13, 1907. Serial No. 378,748.

To all whom it may concern:

Be it known that I, GEORGE W. BARRATT, a citizen of the United States, and residing in the borough of Bellevue, in the county of Allegheny and State of Pennsylvania, have invented or discovered new and useful Improvements in Hammocks, of which the following is a specification.

My invention consists in certain new and useful improvements in hammocks and especially relates to 10 hammocks for the accommodation of infants and young children while sleeping where it is necessary to secure the occupant from climbing or falling out and at the same time avoid too close confinement or pressure. To attain these ends I provide my hammock with 15 bails or spreaders adjacent to the ends thereof and, preferably of curved form and somewhat more than semi-circular in extent. The body of the hammock is made sufficiently full to enable the sides to be drawn up together above the occupant and a cord is inter- 20 laced through the abutting edges, thus forming an inclosed receptacle for the infant or child from which it can neither climb or fall until released by the unlacing of the cord. The bails maintain the hammock body, when laced up, in a substantially circular form, while 25 the top of the hammock may be raised above the face and body of the occupant to the desired degree by regulating the tension of the lacing cord whose ends may be secured to the hammock rings. Thus perfect 30 freedom of motion is obtained without pressure or danger of accident.

In the accompanying drawings, Figure 1 is a longitudinal elevation showing the hammock laced up, Fig. 2 is a plan view showing the hammock partially laced up, a portion of the bottom of the body being 35 cut away for the sake of clearness and Fig. 3 is a vertical section along the line III—III in Fig. 1.

The following is a detailed description of the drawings:

1 is the hammock body, knit of cord 2, and attached 40 at either end to ring 3 by cords 4—4. 5 and 5^a are the bails or spreaders, preferably made of metal rods or heavy wire, one of the same being placed adjacent to each end of the hammock and passed in and out through the strands of said body to hold 45 them in place. I prefer to make said spreaders in substantially the arc of a circle and somewhat more than semi-circular, the ends, 6—6, of the spreaders being preferably bent back on themselves to obtain a better hold on the material of the hammock body. I prefer 50 to make the spreader 5, adjacent to the head of the hammock, somewhat longer and of greater radius than the spreader 5^a, so that the trough like body of the hammock will taper somewhat from head to foot.

The body 1 of the hammock is made sufficiently full

so that the sides may be brought together at the top, 55 as shown in the drawings, and the longitudinal edges 7—7 laced together by means of the cord 8, thus forming an inclosed receptacle for the occupant. The ends of the cord 8 may be secured to the rings 3—3 or at other points, as desired.

9—9 are the usual ropes extending from fixed points, not shown, and secured to the rings 3—3 to hang the hammock.

It is evident that by regulating the tension of the ropes 9—9 the body of the hammock may be allowed 65 to belly down or assume a practically straight position, as desired. By regulating the tension of the lacing cord 8, the top of the inclosed body may be raised or lowered to regulate the capacity of the interior thereof. Thus where a mattress or pillow is placed under the 70 occupant, it would be necessary to draw the cord 8 more tightly to increase the vertical height of the hammock interior to prevent the said top from resting on the face or body of the occupant, the idea being at all times to provide sufficient room for the free move- 75 ment of the occupant.

The use of my invention is as follows:—The cord 8 is unlaced and the sides of the body thrown back to permit the occupant to be introduced, the spreaders 5 and 5^a at all times maintaining the body in its permanent trough like contour, whether occupied or not. After the occupant is settled properly in the trough like body of the hammock, the sides of the body are again brought together at the top and the abutting edges 7—7 are laced together by means of the cord 8 which 80 is tightened sufficiently to raise the upper portion of the body clear from the occupant.

It is evident that the lower portion of the body, extended by the spreaders will at all times maintain its desired contour so that the occupant will rest comfortably therein without pressure, while the inclosed top will prevent the occupant climbing or falling therefrom until released by unlacing the cord 8.

While I have described my hammock as especially fitted for use in the case of infants and young children, 95 it will be understood that it may be made in proper sizes for adults and is useful for use in case of sickness in warm weather as perfect ventilation is thus obtained.

What I desire to claim is:

1. In hammocks, a body portion maintained in substantially the form of a trough and having its sides sufficiently full to be drawn together above said trough like portion to form an inclosed receptacle for the occupant and a member adapted to be interlaced with the abutting edges of said sides to secure the same together, substantially 100 as and for the purpose set forth.

2. In hammocks, a body portion maintained in substantially the form of a trough and having its sides sufficiently full to be drawn together above said trough like portion to form an inclosed receptacle for the occupant, a mem- 105 110

ber engaging the abutting edges of said sides to secure them together and means for regulating the interior height of said inclosed receptacle, substantially as and for the purpose set forth.

- 5 3. In hammocks, a body portion maintained in substantially the form of a trough and having its sides sufficiently full to be drawn together above said trough like portion to form an inclosed receptacle for the occupant, a cord laced through the abutting longitudinal edges of said

sides and means for regulating the tension of said cord 10 whereby the interior height of said inclosed receptacle may be adjusted, substantially as and for the purpose set forth.

Signed at Pittsburg, Penna., this 12th day of June, 1907.

GEORGE W. BARRATT.
